UNITED STATES PATENT OFFICE

120,496

DESIGN FOR A TEXTILE FABRIC OR SIMILAR ARTICLE

William E. Barrott, Aurora, Ind.

Application September 18, 1939, Serial No. 87,273

Term of patent 3½ years

To all whom it may concern:

Be it known that I, William E. Barrott, a citizen of the United States, residing at Aurora, in the county of Dearborn and State of Indiana, have invented a new, original, and ornamental Design for a Textile Fabric or Similar Article, of which the following is a specification, reference being had to the accompanying drawing, forming part thereof.

Figure 1 is a plan view of a textile fabric or similar article, showing my new design.

Figure 2 is a section on line 2—2, Figure 1.

The design comprises a uniform series of folds forming ridges across the width of the material, each fold being alternately depressed and curved at regular intervals forming alternate rows of straight and wavy portions as shown.

I claim:

The ornamental design for a textile fabric or similar article, as shown and described.

WILLIAM E. BARROTT.
